US00D813692S

(12) **United States Design Patent** (10) Patent No.: **US D813,692 S**
(45) Date of Patent: **** Mar. 27, 2018**

(54) **CONNECTED MEASURING SENSOR FOR DETERMINING TEMPERATURE, SOUND, BRIGHTNESS, HUMIDITY, ATMOSPHERIC PRESSURE, AND AIR QUALITY**

(71) Applicant: **ACA O, Aire sur l'adour (FR)**

(72) Inventor: **Alexandre Dugarry, Aire sur l'Adour (FR)**

(**) Term: **15 Years**

(21) Appl. No.: **35/502,107**

(22) Filed: **Nov. 22, 2016**

(80) **Hague Agreement Data**

Int. Filing Date: **Nov. 22, 2016**

Int. Reg. No.: **DM/093686**

Int. Reg. Date: **Nov. 22, 2016**

Int. Reg. Pub. Date: **Dec. 16, 2016**

(51) **LOC (11) Cl. 10-07**

(52) **U.S. Cl.**

USPC **D10/46**

(58) **Field of Classification Search**

USPC D10/46, 52-53, 55, 57

See application file for complete search history.

(57) **CLAIM**

The ornamental design of a connected measuring sensor for determining temperature, sound, brightness, humidity, atmospheric pressure, and air quality, as shown and described.

DESCRIPTION

1. Connected measuring sensor for determining temperature, sound, brightness, humidity, atmospheric pressure, and air quality
